UNITED STATES PATENT OFFICE.

ROBERT G. DAYTON, OF NORTH GRANVILLE, NEW YORK.

TRUNK-HINGE.

SPECIFICATION forming part of Letters Patent No. 268,873, dated December 12, 1882.

Application filed April 18, 1882. (Model.)

To all whom it may concern:

Be it known that I, ROBERT G. DAYTON, of North Granville, county of Washington, and State of New York, have invented certain new and useful Improvements in Trunk-Hinges, of which the following is a full, clear, and exact description, reference being had to the accompanying drawings, and to the letters of reference marked thereon.

10 My invention relates especially to hinges or fastenings employed upon trunks, chests, &c., and has for its object the production of a device which will serve both as a hinge and fastening, cheap and simple to construct, effective in operation, and which will allow the cover or lid of the trunk to be raised from either side, as occasion may require; and it consists essentially in locating upon each side of the trunk one, two, or more separable hinges, one portion thereof being affixed to the body of the trunk, and bearing a movable hasp provided with suitable hooks or projections for interlocking with a second portion of the hinge affixed to the cover or lid, a sliding bar being concealed within the structure of the trunk, adapted and arranged to engage with a locking-tongue upon the hasp, said sliding bar being secured against displacement by a suitable lock; and my invention also involves certain 25 novel and useful combinations or arrangements of parts and peculiarities of construction and operation, all of which will be hereinafter first fully described, and then pointed out in the claims.

30 In the drawings, Figure 1 is a front elevation of a trunk, showing the location and arrangement of the hinges or fastenings; and Fig. 2 is a vertical sectional view at line *xx* of Fig. 1. Fig. 3 is a plan, and Fig. 4 a sectional view, 35 of the hinge enlarged.

Like letters of reference, wherever they occur, indicate corresponding parts in all of the figures.

As ordinarily constructed, the cover of a 40 trunk or chest is adapted and arranged to open but from one side, often necessitating the turning or moving of the trunk in order to reach its contents; but by use of my improved device the cover of the trunk may be raised from 45 either side with equal facility, or, if desired, removed entirely from the trunk and readily replaced and locked thereon.

A is the body of the trunk, constructed of wood or other suitable material in the usual manner, and B is the cover or lid fitting thereon. 55

C is a metal plate, cast, punched, or otherwise formed, and provided with a perforation, C', and ears or projections C², which form the pintle, said plate C being secured to cover B by means of screws or rivets, as at *c*. 60

D is a metal plate, formed in like manner as plate C and affixed to the body of the trunk. In the center of said plate is a perforation, D', and at the top thereof a depression, D², forming half of the pintle-socket, into which the lower portion of plate C fits when the cover is placed in position. A projection, *d*, at each extremity of depression D² prevents lateral movement of the cover and plate C. In the back of plate D, over perforation D', is formed a groove, *d'*, the width thereof being greater in the center than at the extremities, as indicated by dotted lines in Fig. 3. Within said groove is located a wire or spring, *a*, adapted and arranged to engage with a tongue upon the hasp, preventing the same from falling down when not locked in place. At D³ the lower extremity of plate D is bent outward and back, leaving an opening therebeneath, through which a bar, E', upon hasp E passes. 75

E² are hooks, which form the other half of the pintle-socket, and formed upon hasp E, fitting over the ears C² and into perforation C' at the lower extremity of plate C, when the hasp is raised up, and engaging therewith in 80 such a manner as to form a perfectly secure hinge or fastening.

F is a tongue or catch formed upon hasp E, said tongue being cut away slightly at top for the purpose of engaging with spring *a*, and having a cut or notch, *f*, at bottom, through which a sliding bar, G, passes. This bar is concealed within the structure of the trunk, and passes from side to side thereof, as indicated by dotted lines in Fig. 1. At G' the bar is cut away in such a manner as to disengage tongue F when pushed to the right. A pin or knob, H, attached to bar G and projecting through a slot, H', in the side of the trunk, affords ready means for moving the bar in either 90 direction. When the bar is located in such a manner as to engage with the hasp it may be securely held against displacement by the bolt of a lock, I, passing into a notch, G², in bar 100

G, the position of said notch and lock being shown by the dotted lines in Fig. 1.

When constructed and arranged substantially in accordance with the foregoing description, my improved hinge and fastening admirably answers the uses and purposes for which it is intended, as previously indicated. The cover or lid may be opened from either side, or entirely removed from the trunk, as indicated by dotted lines in Fig. 2, and as, when thrown back, plate C finds a support upon hasp E, the use of straps upon the interior of the trunk for holding the cover in an elevated position may be dispensed with. When it is desired to open the trunk upon either side the key is turned in lock I, bar G is drawn back, disengaging hasps E, and by dropping said hasps, as shown at the right of Fig. 1, the cover may be lifted up, the fastenings upon the opposite side acting as hinges.

Having now fully described my invention, what I claim as new therein, and desire to secure by Letters Patent, is—

1. A trunk or chest hinge of the character herein set forth, composed essentially of the two plates for attachment to the body and cover, and the hinged hasp mounted upon one of said plates and interlocking with the other plate, the same being arranged to operate substantially as and for the purposes set forth, whereby the raising of the cover or lid is permitted from either side, and also the removal of the cover or lid, substantially as shown and described.

35 2. In a separable hinge or fastening of the

character herein specified, plate C, perforated at C' and having ears C², substantially as shown and described.

3. In a separable hinge or fastening of the character herein specified, the combination, 40 with plate C, perforated at C' and having ears C², of plate D and hasp E, substantially as shown and described.

4. In a separable hinge or fastening of the character herein specified, plate D, having perforation D', depression D², projections d, bent portion D³, and groove d', substantially as shown and described.

5. In a separable hinge or fastening of the character herein specified, the combination, 50 with plate D, having perforation D' and groove d', of hasp E and spring a, substantially as shown and described.

6. In a separable hinge or fastening, hasp E, having bar E', hooks E², and tongue F, 55 substantially as shown and described.

7. In a separable hinge or fastening, the combination, with plates C and D and spring a, of hasp E, having tongue F, with groove d', substantially as shown and described. 60

8. The combination, with plates C and D and hasp E, of a sliding bar, G, and lock I, substantially as shown and described.

In testimony that I claim the foregoing I have hereunto set my hand in the presence of 65 two witnesses.

R. G. DAYTON.
